UNITED STATES PATENT OFFICE.

JOHN C. PEARSON, OF TUSCALOOSA, ALABAMA.

DESIGN FOR AN INKSTAND.

Application filed April 5, 1926. Serial No. 17,194. Term of patent 3½ years.

To all whom it may concern:

Be it known that I, JOHN C. PEARSON, a citizen of the United States, residing at Tuscaloosa, in the county of Tuscaloosa and State of Alabama, have invented a new, original, and ornamental Design for an Inkstand, of which the following is a specification, reference being had to the accompanying drawing, forming part thereof.

The figure is a perspective view of an inkstand showing my new design.

I claim:

The ornamental design for an inkstand as shown.

JOHN C. PEARSON.
